Guy Cunningham
Attorney.

UNITED STATES PATENT OFFICE.

CAROL L. STRAUSS, OF BANGOR, MAINE.

GARMENT SUPPORTER.

Application filed March 9, 1926. Serial No. 93,492.

This invention consists of a pinless grip for a detachable hose supporter or shoulder strap or similar device.

Figure 1 is a side elevation of my invention with both members engaged.

Figure 2 is a front elevation of the gripping member.

Figure 3 is a front view of the gripped member.

10 Figure 4 is a front view of both members engaged.

Figure 5 is a front view of both members being partially engaged or partially disengaged.

15 Figure 6 shows a front view of a modified form of gripping member.

Figure 7 shows a front view of such modified member with the gripped member being disengaged.

20 The gripped member consists of a metal plate 1, preferably of substantially the width of the elastic of the hose supporter, bent over the end of the elastic 2 and firmly attached thereto by a series of punched portions 3, 3.

As here shown the front portion 4 of the plate 1 is slightly wider than the elastic 2 and the back portion 5 of the plate 1 is the same width as the front but shorter. The 30 back portion 5 may, however, be narrower than the front portion.

The gripping portion consists of an elongated loop or ring 6 the interior of which is so fitted to the gripped portion that the gripped portion cannot draw through the loop except when presented thereto endwise. This gripping portion should have an interior long diameter substantially identical with the width of the elastic 2 of the 40 gripped member. As here shown the long diameter may be slightly less than the width of the front portion 4 of the plate 1. The short diameter should be slightly less than the thickness of the 45 gripped member from front to back.

The gripping member is attached to a corset or other garment in any suitable manner, as by a cloth strip 7, to which it is sewed.

In practice the lower portion of the 50 gripped member will spring outward slightly and is shown as bowed out. It will be seen that when the two members are engaged as in Figure 1 the strain of the elastic will draw the gripped member downward at the 55 front so that the outward portion of the

gripping member will be held under the end of the gripped portion and close to the elastic so as to be free from any chance of disengagement.

The members are engaged by slipping the 60 gripped member endwise through the gripping member as shown in Figure 5, the spring of the gripping member being sufficient to permit such engagement.

In Figures 6 and 7 I have shown a modification of my invention. The gripping member is shown as made of a comparatively rigid plate having a notched portion 8 at one side through which the gripped member may be passed endwise.

In this specification the extent of the plate from a to a , Fig. 3, is for convenience called the width and its extent from front to back the thickness and the other dimension the length.

The gripped member may be reversed so that the front portion 4 will be next to the body of the wearer, thus decreasing the chance of accidental detachment when the wearer is sitting. In that case, I prefer to 80 make the front plate flat or bowed-in slightly rather than bowed-out.

I claim:—

1. An attaching device for a hose supporter having a gripping member having an oblong looped portion, and a gripped member adapted to be passed through the opening endwise only, said gripped member consisting of a strip of hose-supporting fabric having bent over the end thereof a metal plate 90 attached to said fabric at a point above the lower edge of the plate so as to form an engaging tongue, said plate in cross section being approximately the same as the short interior diameter of the loop of the gripping member and in width being greater than the longest interior dimension of the gripping member said gripping member consisting of a loop of wire having a long interior diameter not materially greater than the width 95 of the hose supporting fabric and a short interior diameter through which the gripped member may be passed endwise only, one side of said gripping member being permanently attached, as by stitching, to the supporting garment.

2. An attaching device for a garment supporter consisting of a metal end plate attached to the top of the hose supporting fabric so as to provide an overhanging lip, 110

said plate being slightly wider than the hose supporting fabric, an oblong metal loop secured to the supporting element having interior dimensions slightly larger than the 5 hose supporting fabric, and so proportioned with reference to the end plate that said end plate may be passed through the loop endwise but not sidewise and so that under the strain of wear the overhanging tongue will 10 be hooked over the lower edge of said loop and bear against it.

3. An attaching device for a hose supporter consisting of an oblong loop of metal adapted to be secured permanently, as by 15 stitching, to the garment to which the supporter is to be attached constituting the gripping member and a gripped member consisting of a plate as wide as the supporting elastic and longer than the short interior 20 diameter of the loop, said plate being attached permanently to the top of the hose supporting fabric and forming the upper end thereof, said gripping loop having its longest interior dimension less than the 25 width of the plate and as great as the width of the supporting elastic and an interior short diameter less than the length of the plate and great enough to permit the plate to be passed through it endwise whereby, 30 when engaged, the gripped plate bears

against the lower part of the gripping loop and is supported thereby.

4. An attaching device for a hose supporter having a gripping member having an oblong looped portion, and a detachable 35 gripped member adapted to be passed, and re-passed through the loop endwise only, said gripped member consisting of a metal plate bent over the end of a strip of hose supporting fabric attached to said fabric 40 at a point above the lower edge of the plate so as to form an engaging tongue, said plate being approximately as thick as the short interior diameter of the loop of the gripping member and in width being greater than the longest interior dimension of the gripping member, said gripping member consisting of a loop of wire having a long interior diameter not materially greater than the width of the hose supporting fabric and a 45 short interior diameter less than the length of the plate through which the plate may be passed endwise, one side of said gripping member being adapted to be permanently attached, as by stitching, to the supporting 50 garment.

In testimony whereof, I have signed my name to this specification.

CAROL L. STRAUSS.
